RAILROAD PASSENGER CAR

Walter C. Keys, Detroit, Mich., James A. Younglove, Highland Park, Ill., and Robert D. Gartrell, Oakland, and Richard H. Hambidge, Nutley, N. J., assignors, by mesne assignments, to United States Rubber Company, New York, N. Y., a corporation of New Jersey

Application October 7, 1938, Serial No. 233,708

2 Claims. (Cl. 105—15)

This invention relates to railroad cars having a vestibule entrance extending between the adjacent coupled ends of the cars which are closed at least in part by a diaphragm. The invention relates particularly to the improved connection between the diaphragms and the ends of the cars, or vestibules extending between such ends.

Heretofore the vestibules of railway cars have been provided with diaphragms to protect the vestibule entrances from the outside weather condition. The connection between the diaphragms and the rigid walls of the vestibules have been so constructed that when the diaphragms were placed under tension, due to the relative movement between the ends of the cars or the spring tension operating thereon, an uneven strain was placed upon the margins of the diaphragms along the line of connection between it and the rigid walls of the ends of the cars or vestibules. This was caused in some cases by securing the diaphragms with rivets or bolts. In accordance with the present invention an improved connection is provided between the diaphragms and the rigid walls whereby the tension applied to the diaphragms is distributed evenly along the margins where the connection is made. The load being distributed uniformly along the line of connection, the concentration of forces in the margin of the diaphragm is eliminated and this frequent cause of failure due to the uneven distribution of forces is substantially eliminated. Another object of the present invention is to provide a construction which will facilitate the attachment of the diaphragm to the vestibule or car end.

The foregoing and other objects and features of this invention are disclosed more in detail in the following description and the accompanying drawing:

Fig. 1 is a partial horizontal view of the ends of two articulated cars, showing an embodiment of the invention;

Fig. 2 is a fragmentary vertical section on line 2—2 of Fig. 1;

Fig. 3 is a cross-sectional view of the improved connection between the vestibule or car end; and

Fig. 4 is a modified form of the improved connection.

This invention is illustrated in reference to an articulated car of the type shown in U. S. Patent No. 2,056,227 granted October 6, 1936 to W. H. Mussey, et al. Each of the adjacent ends 10 of the cars are supported on the same truck on a common pintle point 11. The particular construction of the car is not important to this

invention, and only such details will be described as are necessary for the understanding of the invention. The side and roof sheets 12 and end sheets 13 are secured to a corner post 14. The inner edges of the end sheets 13 are connected to end posts 15 to which is secured the door posts 16. The vestibule unit 17 is of the cylindrical type and is fixed to the same truck on which the ends of the cars are supported and is mounted centrally over the axis of the pintle center 11. The vestibule unit 17 comprises a cylindrical sheet of metal 18 having openings 19 therein opposite the space between the door post 16, forming the passageway between the cars. The cylindrical sheet 18 is retained in place between the ends of the cars by means of spring pressed rollers 20 mounted in slides 21 which operate within guide boxes 22 formed in the end post 15. Flexible inner vestibule diaphragms 23, extending between the end posts 15 and the cylindrical sheet 18 and connected to the respective members, form seals between the ends of the cars and the vestibule unit 17.

The vestibule unit 17 is provided with an outer diaphragm 24 having one of its marginal edges attached to the side and roof sheets 12 by a connection 24^a, and the other marginal edge is attached to a U-shaped strip 25^a secured by means of a bracket 25^b to a pivoted arm 25 which retains the outer diaphragm 24 under tension. The arm 25 is pivoted on a bracket 26 which is secured to the cylindrical sheet 18 of the vestibule unit 17. A tension spring 27 extends from the bracket 26 to an arm 28 on the main arm 25 and resiliently holds the main arm 25 away from the end of the side and roof sheet 12 to which the outer diaphragm 24 is attached, and thereby maintains it under tension.

As shown in Fig. 2, the U-shaped strip 25^a extends up the side and across the top and down the other side of the car and operates within a weather shed 29 which is attached to the rear end of the forward car. Rollers 30 are carried by the bracket 25^b which forms a connection between the arm 25 and the U-shaped strip 25^a and cooperate with the weather shed 29.

The connection 24^a between the margin of the diaphragm 24 and the side and roof sheet 12 and the U-strip 25^a is shown in detail in Fig. 3. The outer diaphragm 24 is preferably made of elastic rubber composition and is provided with a bead 31 having a flexible relatively non-flowable insert 32 around which the rubber is vulcanized and united thereto. The insert is preferably made of fabric having a friction coating

of semi-hard rubber. The bead 31 fits into a groove 33 formed into a metal shape 34 which may be attached to the side and roof sheet 12 or to the U-strip 25^a. As shown in Figs. 1 and 3 the metal shape 34 is attached to the side and roof sheet 12, or the U-strip 25^a, as the case may be, by means of bolts 35. The diaphragm 24 extends through a narrowed opening 36 formed in the groove 33. The bead 31 is provided with a sloping edge 37 and cooperates with a corresponding sloping shoulder in the groove 33. The width of the opening 36 as measured between the surfaces thereof on the opposite sides of the diaphragm 24 being less than the thickness of the bead 31 as measured in the corresponding direction, the bead is retained in the groove 33. The terms "width" as applied to the opening and "thickness" as applied to the bead are herein-after used in the above sense.

The bead 31 is provided with an outer layer of fabric 38 which protects the rubber from being chafed by the inner walls of the groove 33 upon the movement of the bead therein. The sloping edges 37 on the bead and the corresponding sloping shoulder 36^a on the walls of the groove 33 are provided to equalize the pressure on the bead throughout its length when tension is applied to the diaphragm 24. In this form of connection the metal shape 34 extends along the ends of the side and roof sheets, and may be made in one or more sections. In order to attach the diaphragm, the bead 31 is inserted in the groove 33 by slipping the bead lengthwise through the groove before the metal shape 34 is attached to the side and roof sheet 12.

A modified form of connection is shown in Fig. 4. In this construction the diaphragm 39^a has a bead 39 which is provided with only one sloping edge 40 and fits in a groove 41 which may be opened by a removable side 42. A grooved metal shape 43 forming the other side of the groove is permanently secured to the end sheet 13 by rivets 44. The bead 39 is provided with a flexible insert 45 and an outer layer of protective fabric 46 similar to the insert 32 and protective layer of fabric 38 respectively, as shown in Fig. 3. In order to assemble the diaphragm, the plate 42 is removed by means of the screws 47. When the groove 41 is opened, the bead 39 may be inserted therein and it is retained in place when the plate 42 is replaced.

It is intended that the inner vestibule diaphragms 23 may be provided with similar connections as shown in Figs. 3 and 4 for securing the margins of the diaphragm to the ends of the cars or to the cylindrical metal sheet 18 forming a part of the vestibule 17. It is also intended that the term "vestibule" as used herein refers to the space between the adjacent ends of the cars of a train and that the term "vestibule diaphragm" refers to either the outer or inner diaphragm. It is further contemplated that the vestibule diaphragms may be stretched between and attached to the adjacent ends of cars provided with separate trucks and having the common coupling extending therebetween. In such case the elasticity of the diaphragms are sufficient to permit them to stretch an amount greater than the maximum variation between the

lines of attachment along the adjacent ends of the cars when passing from a straight track to a curved track. It will be also understood that changes in the detail as shown and described herein may be made without departing from the spirit of the invention and scope of the claims appended hereto.

Having thus described our invention, what we claim and desire to protect by Letters Patent is:

1. The combination in a railway car of a vestibule flexible diaphragm for said vestibule, and of means for connecting said diaphragm to the end of said car comprising a marginal bead formed on the edge of said diaphragm and merging into the surface of the diaphragm, a member secured to the end of said car and having a groove formed therein which retains said bead, said groove having an opening the width of which is less than the thickness of said bead and through which said diaphragm projects, said groove having a throat leading directly to said opening in the lengthwise direction of the car, said throat forming an abutment for the sloping side of said bead and conforming substantially to the shape of the surface of the bead contacting therewith, said bead and groove having a center line lying substantially in a plane perpendicular to the lengthwise direction of the car, said bead having a sliding fit in said groove and thereby being adapted to be pulled as a whole by the diaphragm towards said opening and wedged in said throat and thereby support the entire pull on said diaphragm.
2. The combination in a railway car of a vestibule, an elastic rubber composition diaphragm for said vestibule, and of means for connecting said diaphragm to the end of the car, said diaphragm having a marginal bead provided with a relatively hard flexible core consisting of fabric treated with a friction coating of semi-hard rubber, said core being surrounded by the margin of said diaphragm to form said bead, said bead having a cross sectional shape which slopes towards said diaphragm and merges into its surface, an outer layer of fabric incorporated into said bead and extending along said diaphragm beyond said bead, and said bead fitting into a retaining groove formed in a member attached to the end of said car, said groove having an opening through which said diaphragm projects, the width of said opening being less than the thickness of said bead, said groove having a throat leading directly to said opening in the lengthwise direction of the car, said throat forming an abutment for the sloping edge of said bead and conforming substantially to the shape of the surface of the bead contacting therewith, said bead and groove having a center line lying substantially in a plane perpendicular to the lengthwise direction of the car, said bead having a sliding fit in said groove and thereby being adapted to be pulled as a whole by the diaphragm towards said opening and wedged in said throat and thereby support the entire pull on said diaphragm.
